A. KNUBEL

PROCESS FOR MAKING HAND WHEELS

Filed Dec. 31, 1920

Fig. 2

Fig. 3

UNITED STATES PATENT OFFICE.

ANTON KNUBEL, DECEASED, BY FELIX KÖSTER, ADMINISTRATOR, OF MÜNSTER, GERMANY, ASSIGNEE TO HELENE KNUBEL, OF MÜNSTER, GERMANY.

PROCESS FOR MAKING HAND WHEELS.

Application filed December 31, 1920. Serial No. 434,401.

(GRANTED UNDER THE PROVISIONS OF THE ACT OF MARCH 3, 1881, 41 STAT. L., 1313.)

To all whom it may concern:

Be it known that I, FELIX KÖSTER, a citizen of the German Republic, residing at Münster, Germany, administrator of the estate of ANTON KNUBEL, late a citizen of the German Republic, represent that said ANTON KNUBEL invented certain new and useful Improvements in and Relating to Processes for Making Hand Wheels; and I do hereby declare the following to be a full, clear, and exact description of the invention, such as will enable others skilled in the art to which it appertains to make and use the same.

This invention is covered by foreign applications filed and patented as follows: Germany, K. 61959 XII/39 a 6th March 1913, Patent No. 318383 dated 19th March, 1919; Austria A. 3796 13th August, 1917, Patent No. 77758 dated 28th February 1919; Sweden 2676/19 7th June, 1919, patent pending; France No. 114,570 30th June, 1919, Patent No. 518,631 dated 6th January, 1921; Belgium No. 225048, 11th June, 1919, Patent No. 280376 dated 20th May, 1920; Luxembourg No. 11436 dated 14th June, 1919; Denmark No. 1596/19 6th June, 1919, Patent No. 25836 dated 31st March, 1920; Switzerland No. 99787 4th June, 1919, Patent No. 48966 dated 16th February, 1920; Italy No. 36729 11th June, 1919, Patent No. 518193 dated 25th May, 1921; Czechoslovakia No. 14881 21st June 1921; no patent granted; England No. 17071 23d June 1920, Patent No. 146132 dated 25th August, 1921.

In aircraft and the like it is often usual to employ steering wheels (hand wheels) of which the spokes are made of metal, for example, aluminium or steel sheet, etc., while the rim, which is preferably hollow, consists of celluloid or other similar material which is plastic or bendable under heat.

The present invention consists in a process for connecting these two parts together in such a manner that no cutting or piercing of the rim is necessary at the parts which are to be fastened together and consequently

the slots which formerly were frequently required in the rim and the holes for the connection between the rim and the spokes are entirely avoided.

A form made in two or more parts for carrying out the method according to the invention is shown diagrammatically in the accompanying drawing in Figs. 1 and 2. Fig. 1 shows a plan of the lower part of the form with the rim of the wheel inserted, the upper part of the form being removed. Fig. 2 shows a cross section of the closed form. Fig. 3 is a view partly in section and partly in plan of a completed wheel. The process of construction is as follows:

First, a wheel hub and spokes are made of suitable metal as shown in Fig. 1. According to the invention the spokes *r* are provided at their ends with lateral extensions *f* which are inserted in an annular recess provided in the lower half of the form, the rims of the upper and lower parts of the form being provided with the usual locking screws *r'*.

A hollow rod *a* of celluloid or other similar material and of correct length is softened by immersion in hot water and is then bent by suitable means into the form of a circle. The ends are then again warmed and one end enlarged by a drift and the ends are now inserted in one another so far that a rim of exactly the required circumference is obtained.

The rim is, after it has been again softened by warming, inserted in the form shown in Fig. 1 and the upper part of the form is then placed on and secured by means of the locking screws.

The annular space of the closed form is oval in cross section. The breadth is somewhat greater than the diameter of the circular cross section of the rim. Consequently, the soft rim can be pressed somewhat to one side where the lateral extensions *f* of the spokes lie in the form so that the rim can be inserted in the form.

After the form has been closed it is pref-

erably again placed in hot water, so that the rim has the necessary pliability. At the same time, as shown at *x* in Fig. 2, an opening is bored in the rim, the boring tool being inserted through an aperture provided in the upper part of the form, and in said aperture of the upper part of the form a nipple is screwed. If compressed carbonic acid, steam, etc., is admitted through the nipple it enters into the interior of the rim and causes the latter to permanently shape itself to the interior of the form. The wall of the rim closes tightly about the lateral extensions of the spokes and connects the rim and the spokes without the necessity of cutting out any parts from the rim. As Fig. 3 shows, the material is somewhat stretched at the parts connecting the rim and the spokes and a firmer hold is maintained so that any fracture at these parts is avoided, which otherwise may very easily occur if the rim is cut for the purpose of inserting the lateral extensions of the spokes.

After the rim has been fully expanded it is allowed to cool, the form is opened, the prepared wheel is removed and now only requires to be polished.

If it is desired to provide the upper surface of the rim with flutings or the like in order to make it more easily grasped, or to provide lettering or the like, stencils can be laid in the lower half of the form before the celluloid tube is inserted.

I claim:

1. The process herein described of making hand-wheels having a hollow celluloid rim and spokes of different material, consisting in first heating the hollow rim to soften it, then placing it in a form or mold with the inner face of the rim abutting the ends of the spokes, then admitting a fluid to the interior of the rim to expand the same around the ends of the spokes so that said ends of the spokes will extend into depressions in the rim, and then permitting the rim to harden to thus interlock the rim with the ends of the spokes.

2. The process herein described of making steering-wheels having a hollow celluloid rim joined to the ends of spokes, said rim being originally circular in cross-section, consisting in first rendering the rim pliable by heating the same, then laying the rim thus heated into a form of non-circular cross-section, then admitting a fluid to the interior of the rim to expand the same to conform with the non-circular cross-section of the form and to also envelop the ends of the spokes, and then permitting the rim to harden to thus interlock the rim with the ends of the spokes.

3. The process herein described of making steering-wheels having a hollow celluloid

rim joined to the ends of spokes, said rim being originally circular in cross-section, 65 consisting in first rendering the rim pliable by heating the same, then laying the rim thus heated into a form of non-circular cross-section, then admitting a fluid to the interior of the rim to expand the same to 70 conform with the non-circular cross-section of the form and to also envelop the ends of the spokes, and then permitting the rim to harden to thus interlock the rim with the ends of the spokes, said spoke-ends being 75 enlarged in both directions laterally to thereby provide a greater connecting surface with the rim.

4. The process herein described of making hand-wheels having a hollow celluloid rim 80 and spokes of different material, consisting in first heating the hollow rim to soften it, then placing it in a form or mold with the inner face of the rim abutting the ends of the spokes, then admitting a fluid to the interior of the rim to expand the same around the ends of the spokes so that said ends of the spokes will extend into depressions in the rim, and then permitting the rim to harden to thus interlock the rim with the 85 ends of the spokes, said rim consisting of a straight tube bent into circular form and having its ends connected by being telescoped one into the other.

5. The process herein described of making 90 hand-wheels having a hollow celluloid rim and spokes of different material, consisting in first heating the hollow rim to soften it, then placing it in a form or mold with the inner face of the rim abutting the ends of the 100 spokes, then admitting a fluid to the interior of the rim to expand the same around the ends of the spokes so that said ends of the spokes will extend into depressions in the rim, and then permitting the rim to 105 harden to thus interlock the rim with the ends of the spokes, the cross-section of the annular space of the form being oval, the breadth being greater than the height, and the rim being somewhat smaller in breadth 110 than the space to permit it to be inserted in the form on the outside of the ends of the spokes.

6. The process herein described of making 115 hand-wheels having a hollow celluloid rim and spokes of different material, consisting in first heating the hollow rim to soften it, then placing it in a form or mold with the inner face of the rim abutting the ends of the 120 spokes, then admitting a fluid to the interior of the rim to expand the same around the ends of the spokes so that said ends of the spokes will extend into depressions in the rim, and then permitting the rim to 125 harden to thus interlock the rim with the ends of the spokes, stencils being inserted

in the form so as to thereby provide the rim with such indentations or projections as are desired.

7. The method of attaching the grip-rim to the spokes of a steering-wheel consisting in softening a hollow rim of plastic material, then by interior fluid pressure causing the wall of the rim to closely envelop the ends of the spokes without disrupting

the wall, and then permanently locking the ¹⁰ rim to the spokes by permitting the rim to harden.

FELIX KÖSTER,

Administrator of Anton Knubel, deceased.
